INVENTOR

S. A. KORNSWEET

M. O. Smith

ATTORNEY

UNITED STATES PATENT OFFICE.

SAMUEL A. KORNSWEET, OF LOS ANGELES, CALIFORNIA.

GAME APPARATUS.

Application filed July 27, 1927. Serial No. 208,635.

This invention is a game apparatus comprising targets adapted to be struck by suitable projectiles, and it is the object of the invention to provide an apparatus of novel 5 appearance adapted to arrest the attention of prospective players and including a plurality of playing units differing in the type and degree of skill which must be exercised in playing the game, thereby adapting the 10 apparatus to players of varying skill and also permitting the players to choose their targets in accordance with individual fancy.

It is a further object of the invention to provide signalling means for definitely indicating when the targets have been struck, and to also provide for readily restoring the targets and their signalling means to normal position after each play.

More particularly it is an object of the invention to provide a playing unit in which the target is struck by skipping a projectile across the surface of water, with the targets preferably simulating the appearance of animate objects floating upon the surface of 25 the water, and adapted to be knocked over when struck by the projectiles.

Further objects of the invention will be readily understood from the following description of the accompanying drawings, in 30 which:

Fig. 1 is a plan view of the game apparatus.

Fig. 2 is a front perspective view of the same.

Fig. 3 is a fragmentary vertical section through one of the playing units showing its target.

Fig. 4 is a similar view showing the actuating mechanism for the signalling means.

Fig. 5 is a similar view showing the signalling means.

Fig. 6 is a view similar to Fig. 4 but showing the target and signal actuating mechanism for a different type of playing 45 unit.

Fig. 7 is a similar view showing the target and signal actuating mechanism of a still different type of playing unit.

Fig. 8 is a similar view showing a still 50 further modification.

Fig. 9 is a vertical section through the front of the game apparatus showing one type of projecting means for the projectiles.

The game apparatus comprises a trans- 55 verse counter 1 with a plurality of game alleys extending rearwardly therefrom and

separated by upstanding longitudinal partitions 2. The rear of the apparatus comprises a transverse platform 3 forming an abutment surface 4 at the rear of the alleys, 60 and a backing 5 preferably extends upwardly at the rear of the platform.

The game alleys thus provide a plurality of playing units adapting the apparatus for simultaneous play by a number of players 65 standing in front of counter 1, and in order to provide different tests of skill and permit the players to select their targets in accordance with the dictates of individual fancy, the targets for the respective alleys prefer- 70 ably differ one from another, and different types of projectiles may be used for the different targets.

As an instance of this arrangement, one of the game alleys shown at A, may have supports 6 projecting upwardly from its base with targets 7 hinged to the supports as shown at 8 so that the targets are adapted to be knocked over rearwardly when struck by a suitable projectile; and the targets may 75 be placed at different distances from counter 1 with certain of the forward targets partially protecting the rear targets as shown in Fig. 1 so that different degrees of skill must be exercised in striking and knocking 80 over the respective targets. The projectiles which the player uses for striking the targets may be of a type adapted to be skipped across the surface of water, and for this purpose may comprise flat discs 9 of a suitable material such as rubber, and the game 85 alley A forms a shallow receptacle for water which stands at a level concealing the supports and giving the targets the appearance of floating on the surface of the water. The 90 targets may simulate the appearance of animate objects and in the present instance are shown as representations of ducks or the like.

Another of the game alleys, shown at B, 100 may be adapted for employment of the flat disc projectiles 9 by sliding them across a smooth supporting surface instead of skipping them along the surface of water, but an illusion of a skipping action is preferably 105 maintained by forming the game alley as a shallow receptacle filled with water and covered with a transparent supporting surface of glass or the like as shown at 10. The glass 10 thus forms a smooth surface along 110 which the discs 9 may be slid but leaves the water beneath it visible to the players, and

the player's attention may be detracted from the glass supporting surface and drawn to the body of water beneath it, by placing live fish or the like in the shallow aquarium 5 which is thus formed. The targets employed in this type of game alley are preferably mounted on the rear abutment surface 4, and may comprise suitable normally upright bull's-eyes 11 pivoted as shown at 12 so as 10 to swing rearwardly beneath platform 3 when struck by the discs 9 slid along the glass surface 10.

The discs 9 instead of being simply held in the hand for projecting them along the 15 game alleys, may be projected by a suitable manually controlled paddle 13 which is illustrated as adapted for use in connection with the game alley shown at C. The paddle is hinged at its lower end to the front of 20 counter 1 as shown at 14, so that its upper swinging end projects slightly above the counter medially of alley C, and a projectile which may be one of the discs 9 previously described, is placed in slightly overhanging 25 position on the edge of the counter, so that retraction and subsequent projection of the paddle will strike the disc and move it along the game alley. The paddle is yieldably 30 spring projected, as for example by the coil spring 15, whereby the player by grasping the upper end of the paddle may readily retract and then release it so that it will be suddenly projected by its spring to strike the projectile. The targets adapted to be 35 struck by the projectile which is thus moved along the game alley may be of any suitable type and are shown as bull's-eyes 11 such as previously described, and the surface of the game alley along which the projectiles are 40 slid to strike the bull's-eyes may be simply a smooth surface 16 of any suitable material extending from counter 1 to the rear abutment surface 5.

The game alley shown at D may provide a 45 still different test of skill, and for this purpose is provided with a smooth base 16 such as previously described, upon which is formed a restricted guideway 17 extending lengthwise of the game alley and terminating at its rear end in a tube 18 which curves upwardly and forwardly and thence downwardly to its open end 19 spaced above the surface of the game alley as shown in Fig. 8. Suitable balls 20 of rubber or the like are 50 adapted to be rolled along the game alley and into the slightly flaring forward end 21 of guideway 17, the balls being thus guided into tube 18, and the object of the game being to cause the balls to travel along the entire length of the curved tube so that they 55 will drop from its open end 19.

The game alley E is also adapted for use 60 in connection with ball projectiles 20 such as previously described, the balls being tossed 65 at a target which comprises a funnel 22 posi-

tioned in front of abutment surface 4. The funnel has its forward flaring end tilted upwardly slightly so that the balls may readily enter the funnel, and the opening at the rear restricted end of the funnel is provided with a pivoted bull's-eye 11 such as 70 previously described and against which a direct strike must be made in order to score a hit.

Each of the game alleys is provided with 75 means for indicating when a target has been struck, and for this purpose signalling means shown as electric lamps 23 are mounted above platform 3 with a separate lamp provided for each of the targets. The lamps 80 may be mounted on backing 5 as shown in connection with the game alleys C, D and E; or they may be contained in suitable representations of animate objects adapted to be illuminated by the lamps and shown at F as 85 representations of fish for use in connection with alley B, and comprising images G of the human form mounted on platform 3 for use in connection with the targets of alley A.

Independent circuits for the respective 90 lamps are shown at 24, and may be connected to a common source of electrical energy (not shown), and are preferably each provided with a manually controlled switch 25 whereby the signalling means for any desired target 95 may be made operative or inoperative. The electrical circuits are each provided with a normally open switch 26 adapted to be closed by impact when the corresponding target is struck, and for this purpose the pivoted bull's-eyes 11 employed in game alleys B, C and E are adapted to directly engage and close the corresponding switches 26 when the bull's-eyes are swung rearwardly 100 as a result of being struck, and the contact 105 arm of the switch 26 employed in connection with the target for game alley D may form one end of a lever 27 pivoted at the open end 19 of tube 18, so that a ball 20 dropping from the open end of the tube will engage the opposite end of the lever for swinging it so as to close the switch, while the switch 26 cooperating with each of the targets 7 employed in game alley A is preferably adapted 110 to be closed by a lever 28 pivoted beneath platform 3, with said levers operatively connected to the respective targets as shown at 115 29, so that when a target is knocked over its operating connection will exert a pull upon the corresponding lever for closing the 120 switch.

After a target has been struck and its indicator illuminated, the target may be restored to normal position, permitting its switch 26 to again open by means of a manual control operative from the front of counter 1 and illustrated as comprising an operating medium 30 connected to the target and having a handle 31 arranged whereby longitudinal shifting thereof will restore 130

the target to normal upright position ready for the next play.

I claim:

- 5 1. A game apparatus comprising a game alley forming a receptacle adapted to be filled with water, a target in the alley extending above the water, and a projectile adapted to be skipped across the surface of the water for striking the target.
- 10 2. A game apparatus comprising a game alley forming a receptacle adapted to be filled with water, a pivoted target mounted in the alley and normally extending above the water, a projectile adapted to be skipped across the surface of the water for striking the target and swinging it on its pivot, an indicator, and means for operating the indicator by said swinging of the target.
- 15 3. A game apparatus comprising a game alley forming a receptacle adapted to be filled with water, a pivoted target mounted in the alley and normally extending above the water, a projectile adapted to be skipped across the surface of the water for striking the target and swinging it on its pivot, and a manual control for restoring the target to normal upright position after said swinging thereof.
- 20 4. In a game apparatus of the class described, an alley forming a receptacle adapted to be filled with water, a target in the alley extending above the water, a pro-

jectile adapted to be skipped across the surface of the water for striking the target, a second alley lying parallel with the first- 35 mentioned alley and provided with a restricted guide-way extending lengthwise of said second alley, said restricted guideway terminating at its rear end in an upwardly and forwardly curved tubular portion and a 40 projectile adapted to be thrown forwardly thru the alley and thru the restricted guide-way thereon.

5. In a game apparatus of the class de- 45 scribed, an alley forming a receptacle adapted to be filled with water, a target in the alley extending above the water, a projectile adapted to be skipped across the surface of the water for striking the target, a second alley lying parallel with the first- 50 mentioned alley and provided with a restricted guideway terminating at its rear end in an upwardly and forwardly curved tubular portion, a projectile adapted to be thrown forwardly thru the alley and thru the 55 restricted guideway thereon, a visible indicator to the rear of said second alley, and means actuated by the passage of a projectile thru the upwardly and forwardly curved portion of the restricted guideway for oper- 60 ating said indicator.

In testimony whereof I affix my signature.

SAMUEL A. KORNSWEET.
